WINDING, CONING, AND THE LIKE

Morris Siegel, New York, N. Y., assignor to Malina Company, Inc., New York, N. Y., a corporation of New York

Application April 8, 1936, Serial No. 73,289

1 Claim. (Cl. 242—39)

The present invention relates to a winding apparatus and process for placing yarn or thread upon a spool or bobbin and to the wound product resulting therefrom and it particularly relates to the application of winding and coning machines to the application of a criss-cross wind to spools or yarn or thread containers having flanged ends.

It is among the objects of the present invention to provide an improved winding or coning mechanism which not only will be applicable to applying a criss-cross wind to cones or cylinders, but will also be adapted to applying such a wind to spools having flanged or extension ends.

In accomplishing the objects of the present invention it has been found most satisfactory to utilize a machine which will carry and rapidly rotate a spool or flanged carrier for the yarn or thread, to which rotating carrier, the yarn will be fed by a reciprocating thread guide.

In the preferred construction it is desirable to position the reciprocating thread guide so that its stroke will be substantially inside of the spacing between the flanged ends of the spool or carrier and so that the thread or yarn with the same throw will gradually pile it toward said flanges or extension ends of the carrier to form a firm package of yarn or thread, particularly adapted for textile processing purposes.

The reciprocating carrier is preferably positioned so as to clear the flange or extension ends of the carrier while another device is preferably utilized which may be placed inside the flanges or extension ends of said spool or carrier and serve to throw out the winding mechanism at a predetermined filling of said carrier with yarn or thread.

The above and other objects will appear more clearly from the following detailed description when taken in connection with the accompanying drawings which illustrate a preferred embodiment of the inventive idea.

Referring to the drawings:

Figure 1 is an end view of one form of apparatus, according to the present invention.

Figure 2 is a side view upon line 2—2 of Figure 1.

Figure 3 is a side elevational view of the spool in partial section at the end thereof.

Referring to Figures 1 and 2, the machine frame 10 carries an enclosure 11, within which is positioned the cam 13 rapidly rotated by the shaft 14 driven by the gear 15.

The cam actuates the follower member 16 which is connected to the rod 17, said rod 17

sliding in the recess 18 in the extension member 19.

The rod 17, at its end 20, as shown best in Figure 2, carries the upstanding plate member 21 at the top of which is carried the porcelain thread guide 22.

The porcelain thread guide 22 guides the thread 23 which moves in the direction of the arrow 24, past a stop motion at 25.

The thread also passes over the fixed guide 10 element 26 carried upon the arm 27 attached by the extension 28 to the frame 11 and under the tensioning guide 29 which is connected to the wire frame 30 pivotally mounted at 31 upon the arm 32.

In case of breakage of the thread 23, the element 29 will drop and the left end 33 of the frame 30 will engage one of the recesses 34 in the wheel 35 which turns on the shaft 14.

The engagement of the element 33 with the recess 34 in the wheel 35 will have the effect of pressing upwardly upon the pivot 31 and move the arm 32 in the direction indicated by the arrow 36 in Figure 1 upon its pivot 37 on the frame 11.

The arm is provided with an extension 38 which carries the tooth member 39 engaging the latch 40, said latch 40 being at the end of the curved arm 41 connected to the shaft 42.

The movement of the arm 32 in the direction 30 of the arrow 36 will disengage the face 39 from the tooth 40 permitting the spring 43 connecting upon the arm 44 to rotate the pivot rod 42.

The pivot rod 42, as shown on Figure 2, is pivotally mounted at 45 upon the upper frame 35 extension 46 and is connected by the lever 47 and the rotating disk 48 to the clutch structure 49. The clutch structure 49 is driven through the pinion 50 which in turn is driven from the main gear 15.

The clutch 49 drives the shaft 51 which carries at its outer end the spool carrier 52 having the spring fingers 53 on which a spool with flanged ends 55 may be conveniently grasped.

The yarn or thread guide structure 22 and its 45 bearing 19 are mounted upon the arm 56, the arm 56 is adjustably positioned by the extension 100, the end of which lets in the groove 101 in the arm 32. The arm 56 is pivotally mounted by the sleeve 57 and is provided with a counter 50 weight 58. This construction will permit the guide 22 to be positioned so that it will reciprocate beyond the flanges 55 and clear the spool 54.

The contact member 59 may be conveniently inserted between the flanges 55 of the spool 54 55

to control the depth and thickness of the yarn A, thereof, before the apparatus is thrown out.

The contact member 59 is carried on the arm 60 and is screwed at 61 to the lug 62 carried on the pivot 63.

The arm 60 is split and provided with the adjustment thumb screws 64, 65. At its end it has a concave element 66 which fits under the pin 67 attached to the arm 32. As a result pressure 10 on the contact element 59 by the yarn A in the direction indicated by the arrow 68 will throw out the mechanism.

In operation, the shaft 14 will rotate the cam 13 reciprocating the thread guide 22 which has 15 been set by the arm 56 to clear the flanges 55.

The spool 54, placed upon the carrier 52, 53, is rotated by the shaft 51 and will draw the thread past the guides 26 and 28 of Figure 1, giving it a criss-cross wind, as indicated in Figure 3.

20 The thread will gradually pile up from between the points 69, as indicated in Figure 3, to the point 70, where it will closely pack against the flanges 55 of the spool 54, forming a package of maximum utility for textile processing.

25 The packages shown in Figure 3 will permit removal of the yarn 23 over the flanges 55 without interference, tangling or undue tension or breakage whether such yarn is to be rewound upon a cone or whether it is used for knitting 30 upon a knitting machine or whether it is to be prepared for weaving either as a warp or weft.

The important feature of the package of Figure 3 resides in the fact that the yarn adjacent the core will be substantially spaced away from 35 the flanges 55 and will approach the flanges adjacent the periphery thereof.

The control element 59 in the meanwhile, will be set inside of the flanges 55 so that it will be moved in a direction 68, when a suitable amount 40 of filling has been applied.

Both the control element 59 and the thread guide 29 will cause a throwing out and stopping of the machine by disengagement of the clutch 49 through unlatching of the connection 38, 40, shown in Figure 1.

5 This stoppage of the machine will be caused by a movement of the lever 32 in the direction of the arrow 38.

The machine may be restarted most conveniently by the actuation of the hand lever 61 10 pivotally mounted at 72 and having the depending finger 73.

15 It is to be understood, however, that all these variations and alterations as well as any other changes or modifications within the scope of the invention are all to be included herein and the invention is not to be limited to the specific embodiment above-illustratively set forth.

What is claimed is:

A yarn or thread package comprising a spool with a central elongated cylindrical portion and circular end flange members permanently connected to said central cylindrical portion, the inside faces of said circular end flange members 25 lying in a plane perpendicular to the axis of the spool, and yarn or thread wound in a compact annular mass and in a criss-cross fashion upon said cylindrical portion, said body of yarn or thread being wound upon said cylindrical portion 30 so that it will be spaced substantially away from said end flange members at said cylindrical portion and will extend outwardly toward said end flange members toward the periphery of the annular yarn mass so that the yarn body is compacted against said flange at its periphery whereby said yarn may be more readily wound upon said spools and may be more readily removed from said spools in textile processing.

MORRIS SIEGEL.
